No. 721,774.

PATENTED MAR. 3, 1903.

R. B. BENJAMIN.
PLURAL LAMP SOCKET.

APPLICATION FILED MAY 20, 1898. RENEWED AUG. 10, 1901.

NO MODEL.

UNITED STATES PATENT OFFICE.

REUBEN B. BENJAMIN, OF CHICAGO, ILLINOIS, ASSIGNOR TO THE BENJAMIN ELECTRIC MANUFACTURING COMPANY, OF CHICAGO, ILLINOIS, A CORPORATION OF ILLINOIS.

PLURAL-LAMP SOCKET.

SPECIFICATION forming part of Letters Patent No. 721,774, dated March 3, 1903.

Application filed May 20, 1898. Renewed August 10, 1901. Serial No. 71,635. (No model.)

To all whom it may concern:

Be it known that I, REUBEN B. BENJAMIN, a citizen of the United States, residing at Chicago, in the county of Cook and State of Illinois, have invented a certain new and useful Improvement in Plural-Lamp Sockets, of which the following is a full, clear, concise, and exact description, reference being had to the accompanying drawings, forming a part 5 of this specification.

My invention relates to a plural-lamp socket, my object being to provide a compact and cheaply-constructed form of socket for a cluster of incandescent lamps.

15 I have illustrated my invention in the accompanying drawings, in which—

Figure 1 is a sectional view of a plural socket embodying my invention. Fig. 2 is a plan view of the contact adapted to be engaged by 20 the central terminals of the lamps. Fig. 3 is a plan view of the bowl-shaped contact-plate which supports the contacts adapted to be engaged by the ring-terminals of the lamps. Fig. 4 is a view of one of the individual sockets. Fig. 5 is a sectional view of a modification wherein the socket is adapted to receive lamps having bases of the Thomson-Houston type, and Fig. 6 is a view of a further modification.

30 Like letters refer to like parts in the several figures.

Upon the under side of an insulating-base *a* is supported a bowl-shaped contact-plate *b*, having oblique side walls and being secured 35 at the upper edge to the insulating-base by means of screws *a'* *a'*. Upon the oblique side walls are mounted the threaded shells *b'* *b'* to receive the lamp-bases. Within this bowl-shaped contact-plate and supported upon the 40 insulating-base is a contact-plate *c*, which in the present instance has an upturned rim *c'*, which constitutes the contact adapted to be engaged by the central terminal of the lamp when the base thereof is screwed into the 45 shell *b'*. The plate *c* is secured upon the base *a* by means of screws *c'* *c'*. One of the conductors *d* is connected with the screw *d'*, provided upon the plate *c*, and the other conductor *d'* is connected with a screw *d'*, mounted 50 upon the plate *b*, whereby plates *c* and *b* con-

stitute the opposite terminals of the socket, and when the several lamps are screwed into position they are connected in parallel. A casing *e* surrounds the lower portion of the socket, having openings to accommodate the 55 shells *b'* and having upon the lower end and centrally situated relatively to the individual sockets a removable cap *e'*, which may be removed when it is desired to gain access to the binding-screws *d'* *d'*. The upper portion 60 of the socket is also inclosed within a metal shell *e*, supported in the present instance by a bushing *e*, secured to the pipe *e*.

In Fig. 5 I have illustrated a socket adapted for lamps having bases of the Thomson-Houston type. The contact-plate *b* is similarly supported from the insulating-base *a*, which in the present instance is shown as the base of a wall-socket adapted to be secured to the wall by means of screws *a'* *a'*. The 70 ring-terminal *f* of the lamp-base is adapted to engage the oblique base of the bowl-shaped contact-plate *b*, while the centrally-screw-threaded contact *f'* of the lamp is adapted to screw upon the post *c'*, a number of which 75 are mounted upon a metal base *c*, screwed to the under side of the insulating-base *a*. A casing *e* incloses the metal portions of the socket, as in the former instance.

In Fig. 6 I show how insulating bushings 80 or rings *h* may be applied to the shells *b'* to insulate the casing *e* therefrom to assist in holding the casing in place and to align the apertures in the case with the threaded shells. As shown, these bushings or rings are preferably threaded to permit them to be screwed upon the shells. The bowl-shaped contact-plate in each of the forms illustrated herein 85 forms an electrical conductor to convey current to the ring-terminals of the lamps, thus dispensing with wiring, and at the same time it forms an effective mechanical support without the provision of any additional supporting structure.

Having described my invention, what I 95 claim as new, and desire to secure by Letters Patent, is—

1. In a plural-lamp socket, the combination with an insulating-base, of a metallic bowl-shaped contact-plate mounted thereon and 100

- having oblique side walls provided with a plurality of openings to accommodate the central lamp and socket terminals and carrying the contacts for the ring-terminals of the lamps, contacts for the end terminals of the lamps supported within said bowl-shaped contact-plate and placed opposite the openings therein, and means adapted to secure the lamps in operative relation with said contacts, substantially as described.
2. In a plural-lamp socket, the combination with an insulating-base, of a metallic bowl-shaped contact-plate mounted thereon and having oblique side walls provided with a plurality of openings to accommodate the central lamp and socket terminals, a plurality of metallic threaded shells for the lamp-bases mounted upon said contact-plate and in electrical contact therewith, and contacts for the end terminals of the lamps supported within said bowl-shaped contact-plate and placed opposite said shells, substantially as described.
3. In a plural-lamp socket, the combination with an insulating-base, of a metallic bowl-shaped contact-plate secured at the rim or larger end to said insulating-base and having oblique side walls provided with a plurality of openings to accommodate the central lamp and socket terminals and carrying the contacts for the ring-terminals of the lamps, contacts for the end terminals of the lamps mounted upon said insulating-base within said bowl-shaped contact-plate and placed opposite the openings therein, and means adapted to secure the lamps in operative relation with said contacts, substantially as described.
4. In a plural-lamp socket, the combination with an insulating-base, of a metallic bowl-shaped contact-plate mounted thereon and having oblique side walls provided with a plurality of openings to accommodate the central lamp and socket terminals and carrying the contacts for the ring-terminals of the lamps, contacts for the end terminals of the lamps supported within said bowl-shaped contact-plate and placed opposite the openings therein, means adapted to secure the lamps in operative relation with said contacts, a shell inclosing said bowl-shaped contact-plate and having a series of openings one opposite each of the lamp-openings in said contact-plate and having an opening in the end opposite the bottom plate or portion of said bowl-shaped contact-plate, and a removable or detachable cap for sealing said latter opening, substantially as described.
5. An electric-lamp cluster, comprising a plurality of metallic receivers for the lamps, a metallic truncated portion carrying the receivers and attached to the base, an electric connection with the receivers, an additional contact for each receiver and an electric connection with said contacts, as set forth.
6. An electric-light-lamp cluster, consisting of a non-conductor base, a metallic truncated lower portion attached to the base and having a plurality of lamp-receivers and suitable electric connections extending to said truncated portion, substantially as described.
7. In a plural-lamp socket, the combination with an insulating-base, and a metallic contact-plate mounted thereon, of a plurality of metallic threaded shells for the lamp-bases, supported thereon and in electrical contact therewith, and contacts for the central-lamp terminals arranged opposite the respective shells, substantially as described.
8. In a plural-lamp socket, the combination with a suitable base, of a contact-plate of conducting material mounted thereon having side walls and provided with a plurality of openings to accommodate the central lamp and socket terminals and carrying the contacts for the ring-terminals of the lamps, center contacts for the lamps and means adapted to secure the lamps in operative relation with said contacts, substantially as described.
9. In a plural-lamp socket, the combination with a suitable base, of a plate mounted thereon having side walls provided with openings to accommodate the central lamp and socket terminals, a plurality of threaded shells mounted on said walls, and central terminals for the lamps, substantially as described.
10. In a plural-lamp socket, the combination with a suitable base, of a contact-plate having side walls and attached at its rim to said base, said walls being provided with a plurality of openings to accommodate the central lamp and socket terminals and carrying the contacts for the ring-terminals of the lamps, center contacts for the lamps, and means adapted to secure the lamps in operative relation with said contacts, substantially as described.
11. In a plural-lamp socket, the combination with a suitable base, of a contact-plate mounted thereon having side walls provided with a plurality of openings to accommodate the central lamp and socket terminals and carrying the contacts for the ring-terminals of the lamps, center contacts for the lamps, and means adapted to secure the lamps in operative relation with said contacts, a shell inclosing said contact-plate and having a plurality of openings to accommodate the lamps and another opening centrally arranged with relation to the lamp-openings, and a removable or detachable cap for said latter opening, substantially as described.
12. In a plural-lamp socket, the combination with a suitable base, of a contact-plate mounted thereon having side walls provided with a plurality of openings to accommodate the central lamp and socket terminals and carrying the contacts for the ring-terminals of the lamps, upturned contact portions adapted to be engaged by the central lamp terminals, and means adapted to secure the lamp in operative relation with said contacts, substantially as described.
13. In a plural-lamp socket, the combination

with a base having a central projection, of a contact-plate mounted upon said base and having side walls provided with a plurality of openings to accommodate the central lamp and socket terminals and carrying the contacts for the ring-terminals of the lamps, upturned contact portions constituting the central contacts mounted upon said central projection of the base, and means adapted to secure the lamps in operative relation to said contacts, substantially as described.

14. In a plural-lamp socket, the combination with a base having a central opening, of a contact-plate mounted on said base and having side walls provided with a plurality of openings to accommodate the central lamp and socket terminals, and carrying the contacts for the ring-terminals of the lamps, upturned contact portions constituting the central contacts for the lamps, and means adapted to secure the lamps in operative relation with said contacts, substantially as described.

15. In a plural-lamp socket, the combination with a base having a central projection and an aperture therethrough, of a contact-plate mounted upon said base and having side walls provided with a plurality of openings to accommodate the central lamp and socket terminals, and carrying the contacts for the ring-terminals of the lamps, upturned contact portions constituting the central contacts for the lamps and mounted upon said projection of the base, and means adapted to secure the lamps in operative relation with said contacts, substantially as described.

16. In a plural-lamp socket, the combination with a base having a central aperture, of a contact-plate having side walls provided with a plurality of openings to accommodate the central lamp and socket terminals and carrying the contacts for the ring-terminals of the lamps, a binding-post associated with said plate, upturned contact portions constituting the central contacts for the lamps, a binding-post associated with said central contacts, and means adapted to secure the lamps in operative relation with said contacts, substantially as described.

17. The combination with a suitable base, of a contact-plate of conducting material having a plurality of openings in the side walls thereof to accommodate the central lamp and socket terminals, the said side walls carrying the contacts for the ring-terminals of the lamps, contacts for the center terminals of the lamps, and means to secure the lamps in operative relation with said contacts, substantially as described.

18. The combination with a suitable base, of a contact-plate of conducting material provided with a plurality of openings to accommodate the central lamp and socket terminals and carrying the contacts for the ring-terminals of the lamps, contacts for the central lamp terminals, and means to secure the lamps in operative relation with said contacts, substantially as described.

19. The combination with a suitable base, of a contact-plate of conducting material provided with a plurality of openings to accommodate the second contacts of the lamp-holding devices, lamp-holding devices and associated contacts, said contact-plate carrying one contact of each lamp-holding device, and the second contact thereof being suitably mounted.

20. The combination with a suitable base, of a contact-plate of conducting material having side walls provided with a plurality of openings to accommodate the second contacts of the lamp-holding devices, lamp-holding devices and associated contacts, the side walls of said contact-plate carrying one contact of each lamp-holding device, and the second contact thereof being suitably mounted.

21. A lamp-cluster comprising a suitable base, a truncated portion supported upon said base and having oblique side walls provided with a plurality of openings to accommodate the lamp-bases, a plurality of lamp-receiving shells supported upon said truncated portion opposite said respective openings, a center contact for each shell supported independently of said truncated portion, and electrical connections connecting the shells and center contacts in operative relation, substantially as described.

22. A lamp-cluster comprising a suitable base, a truncated portion supported thereon having oblique side walls provided with a plurality of openings to accommodate the lamp-bases, a plurality of metallic threaded shells to receive the lamp-bases mounted upon said truncated portion opposite said respective openings, and center contacts supported upon said base independently of the said truncated portion, substantially as described.

23. An insulating-base, center contacts carried directly thereon, a metallic plate having oblique side walls provided with openings opposite said center contacts, and shells supported upon said plate opposite said openings.

24. A cluster-lamp fixture comprising an insulating-base, a plurality of lamp-holding devices having contacts supported upon said base and a metallic cover or casing having openings for the passage of the lamp-bases and independent of said lamp-holding devices.

25. A cluster-lamp fixture comprising an insulating-base, a plurality of lamp-holding devices each having two contacts supported upon said base, and a metallic cover or casing having openings for the passage of the lamp-bases and independent of said lamp-holding devices.

26. A cluster-lamp fixture comprising an insulating-base, a plurality of lamp-receiving shells supported by said base and a separate cover or casing.

27. A cluster-lamp fixture comprising an insulating-base, a plurality of threaded shells supported by said base and a separate cover or casing.

28. A cluster-lamp fixture comprising an

insulating-base, lamp-holding devices and their contacts all mounted upon said insulating-base, and a removable cover.

29. A cluster-lamp fixture comprising an insulating-base, lamp-holding devices and associated contacts all mounted upon said insulating-base, and a cover having an opening opposite each lamp-holding device, substantially as described.

30. A cluster-socket comprising a suitable base, lamp-holding devices and associated contacts arranged to hold the lamps in an oblique position relatively to the base, and a cover having an opening opposite each lamp-holding device, substantially as described.

31. A cluster-lamp fixture comprising an insulating-base, a number of lamp-holding sockets with their contacts directly mounted on the insulating-base, and a cover having an opening opposite each lamp-holding device, substantially as described.

32. A cluster-lamp fixture comprising an insulating-base, a number of threaded shells and center contacts constituting the lamp-sockets mounted upon the insulating-base, and a cover having an opening opposite each socket, substantially as described.

33. A cluster-socket comprising a suitable base, lamp-holding devices and associated contacts arranged to hold the lamps in an oblique position relatively to the base and an inclosing cover or casing.

34. A cluster-lamp fixture comprising an insulating-base, a removable cover and a number of lamp-holding sockets with their contacts directly mounted on the insulating-base.

35. A cluster-lamp fixture comprising an insulating-base, and a removable cover, a number of threaded shells and center contacts constituting the lamp-sockets mounted directly upon the insulating-base.

36. A cluster-lamp fixture comprising an insulating-base, lamp-holding devices and their contacts all mounted upon said insulating-base, a removable cover, electrical conductors connecting said contacts and carried upon said base, and means, as binding-posts, supported upon said base for the connection of the leading-in wires.

37. A cluster-lamp fixture comprising an insulating-base, lamp-holding devices and their contacts, all mounted upon said insulating-base, electrical conductors connecting said contacts and carried upon said base, means, as binding-posts, for the connection of the leading-in wires, and a removable cover permitting access to said binding-posts or similar means.

38. An insulating-base, lamp-holding devices and associated contacts, a casing having an opening opposite each lamp-holding device, and means for maintaining the openings in said casing in alignment with said respective lamp-holding devices.

39. A lamp-fixture comprising a suitable

base, a plurality of lamp-holding devices and associated contacts associated with said base, a finishing shell or cover having an opening opposite each of said lamp-holding devices for the passage of the lamp-bases, and a removable cap carried upon said cover.

40. A cluster-lamp fixture comprising a suitable base, a plurality of lamp-holding devices and associated contacts associated therewith, a finishing cap or cover having an opening opposite each lamp-holding device to accommodate the lamp-bases, and a removable cap carried upon said cover and centrally arranged with relation to said lamp-holding devices.

41. A cluster-lamp fixture comprising a suitable base, a plurality of lamp-holding devices and associated contacts associated therewith, a cover having a plurality of openings one opposite each of said lamp-holding devices to accommodate the lamp-bases, and a removable cap upon said cover and centrally arranged with said openings.

42. The combination with a suitable base, a contact-plate attached at its rim to said base, and carrying a plurality of openings to accommodate the second contacts of the lamp-holding devices, lamp-holding devices and associated contacts, said contact-plate carrying one contact of each lamp-holding device and the second contact thereof being suitably supported.

43. The combination with a suitable base, of a contact-plate of conducting material having an outwardly-extending flange secured to said base, said contact-plate being provided with a plurality of openings to accommodate the second contacts of the lamp-holding devices, lamp-holding devices and associated contacts, said contact-plate carrying one contact of each lamp-holding device and the second contact thereof being suitably supported.

44. The combination with a suitable base, of a plurality of lamp-receiving devices and associated contacts suitably supported in front of said base, a finishing cap or cover having an opening opposite each of said lamp-receiving devices to accommodate the passage of the lamp-bases, a bracket adapted to be attached to the rear of said base, a supporting stem or pipe secured to said bracket, and a finishing cover or casing upon the rear of said base inclosing said bracket and having an opening to accommodate the passage of said stem or pipe, substantially as described.

45. In a lamp-socket, an insulating-base, a plurality of threaded lamp-shells occupying oblique positions relatively to the axis of said base and metallic supporting parts for said shells secured to said base by screws or bolts passing axially into or through said base.

46. In a plural-lampsocket, the combination with a suitable base, of a plurality of lamp-receiving shells suitably supported thereon in oblique positions, each of said shells being unobstructed throughout its length to per-

mit the lamp-base to pass completely therethrough, and center contacts for the respective shells situated beyond the inner ends thereof, whereby the lamp-holding devices may be assembled in compact form substantially as described.

In witness whereof I have hereunto sub-

scribed my name in the presence of two witnesses.

REUBEN B. BENJAMIN.
